UNITED STATES PATENT OFFICE.

GUY R. JOHNSON, OF LONGDALE, VIRGINIA.

LOCK-TRIMMING.

SPECIFICATION forming part of Letters Patent No. 427,423, dated May 6, 1890.

Application filed February 26, 1890. Serial No. 341,789. (No model.)

To all whom it may concern:

Be it known that I, GUY R. JOHNSON, a citizen of the United States, residing at Longdale, in the county of Alleghany and State of Virginia, have invented new and useful Improvements in Locks, of which the following is a specification.

My invention relates to certain improvements in locks, the purpose thereof being to provide exceedingly simple and inexpensive means, which may readily be combined with a door-lock of any ordinary construction, whereby the key may be retained therein, and its ready insertion and removal permitted.

It is a further purpose of my invention to provide means of the character specified which shall also afford a complete shield for the key-hole, muffling or preventing the passage of sound, and wholly defeating all attempts to spy through the key-hole by servants or others.

The invention consists to these ends in the several novel features of construction and new combinations of parts, hereinafter fully set forth, and then pointed out in the claims, reference being had to the accompanying drawings, in which—

Figure 1 is a sectional view of a portion of a door, showing a lock of any ordinary construction to which my invention is applied. Fig. 2 is a detail view of the diaphragm-muffler applied to the lock, shown in Fig. 1. Fig. 3 is a detail perspective of the said diaphragm.

In the said drawings, the reference-numeral 1 denotes a section or portion of a door which is provided with a lock of any known or preferred form.

Inasmuch as the invention is applicable to any pattern of lock operated by any ordinary key, no specific description of the lock mechanism is necessary.

The numeral 2 designates the escutcheon of the lock, beneath which I place a sheet, diaphragm, or septum 3, of rubber, felt, leather, or other suitable flexible or elastic material, which may be partly or wholly co-extensive with the escutcheon. This underlying diaphragm or sheet is provided with a small opening 4 for the admission of the shank or shaft of the key, said opening being

substantially concentric with the opening in the escutcheon-plate. From said opening a cut or slit 5 is formed of sufficient length to readily admit the passage of the key in inserting or removing it from the lock.

In practice the opening 4 in the rubber, felt, or other material is preferably made of less size than the shaft or spindle of the key, in order that it may close thereon upon insertion, and by its elastic hold or grip prevent the dropping of the key, which is such a frequent cause of inconvenience and loss. If the material 3 is of proper elasticity or flexibility, this opening 4 may be of extremely small diameter, as compared with the shaft or spindle of the key.

The rubber, felt, leather, or other material of which the diaphragm or muffler is composed may be set in a recess or mortise in the face of the door, or it may be interposed between the plain unmortised face of the door and the escutcheon-plate and held in place by the screws holding the escutcheon. After the key is inserted the elastic or flexible quality of the material composing the muffler enables it to secure a firm hold upon the shaft or spindle, whereby the key is prevented from rattling and falling out of the lock, and the noise ordinarily produced in inserting and withdrawing the key is greatly diminished, as the opening 4 in the muffler serves as a guide for the shaft or spindle, whereby it may be inserted without material contact with the key-opening of the lock. Moreover, after the key has passed through the slit or cut 5, the latter closes by the elasticity of the material, thereby effectually closing the opening and preventing all possibility of looking or spying through the key-hole. This closing of the key-opening also cuts off the passage of sound and prevents the overhearing of conversation carried on in a reasonably low tone.

What I claim is—

1. In a lock, the combination, with the escutcheon or other plate having an opening for the admission of the key, of a diaphragm of rubber, felt, leather or other suitable material lying behind said plate and provided with an opening for the shaft or spindle of the key of less diameter than said shaft, and having

a cut or slit communicating with said opening and extending to the other end of the key hole or opening, substantially as described.

2. The combination, with the escutcheon-
plate of a lock, of a flexible or elastic dia-
phragm having an opening for the shaft or
spindle of the key, and provided with a slit
communicating with said opening and of a

length to admit the key, substantially as de-
scribed.

In testimony whereof I have affixed my sig-
nature in presence of two witnesses.

GUY R. JOHNSON.
